UNITED STATES PATENT OFFICE.

JOSEPH F. BATTY, OF BALTIMORE, MARYLAND.

PISTON AND PACKING RELIEF-VALVE.

1,172,337.

Specification of Letters Patent. Patented Feb. 22, 1916.

Application filed January 16, 1915. Serial No. 2,557.

To all whom it may concern:

Be it known that I, JOSEPH F. BATTY, a citizen of the United States, residing at Baltimore, State of Maryland, have invented 5 certain new and useful Improvements in Pistons and Packing Relief-Valves, of which the following is a specification.

This invention relates to pistons and automatically pressure operated floating valves 10 for relieving the piston packing rings of all steam pressure due to the steam, under high pressure, working in between the rings and their grooves, and is intended primarily for use with steam engines, though capable 15 of use in other arts.

Heretofore it has been common practice to use either steam pressure packing, wherein in some instances means for reducing the pressure behind the packing below that of 20 the steam in the cylinder have been provided, or to use spring snap packing rings, or other means.

In actual practice I have found that steam pressure packing causes undue friction, requiring excessive use of expensive 25 lubricants, reducing the efficiency or power of the engine, and causing unnecessary expense in frequent repair, aside from the initial expense of such pistons. I prefer 30 therefore the usual automatically wear compensating spring snag ring packing, but find, as used with the common piston and steam under high pressure, that the latter will invariably work its way in behind the 35 packing rings, forcing them to expand by such pressure and cause the conditions above mentioned with regard to steam pressure packing to such an extent that after but little operation of the engine it is necessary to 40 replace the packing as being too badly worn. Beside being damaging to the rings it is of course damaging to the cylinder, wearing this out before its time.

The object of this invention therefore is 45 to provide means for automatically permitting the escape of all steam which may work its way behind the piston rings from the charging or working side of the piston to the exhausting side, said means being 50 automatically operated by the compression of the residuum of the exhaust as the piston approaches the end of the cylinder.

To this end my invention consists in the construction, combination and arrangement 55 of parts hereinafter more particularly set forth and claimed.

In the accompanying drawings: Figure 1 is a longitudinal sectional view through the cylinder showing a piston embodying my invention, partly in elevation and partly in section to illustrate the position of the piston and the valves after the latter have been shifted by the compression of the residuum of the previous exhaust and just prior to the entrance of the steam charge; Fig. 2 60 represents a top plan view of the piston; Fig. 3, a section on line 3—3 of Fig. 2, showing the passages with the floating valve in place, this view being on an enlarged scale; Fig. 4, a section on line 4—4 of Fig. 3; and Fig. 5 detail perspective views of the valves 65 and stem.

Referring now in detail to the drawings, A indicates the cylinder provided with supply and exhaust ports and slide valve B, 70 and C indicates the piston rod, all as usual, on which is mounted piston member 1 in any suitable and usual manner as shown.

On member 1 is slipped the concentric member 2 having a horizontal annular part 75 provided with perforations 3 through which bolts 4 are turned into registering internally screw-threaded bolt holes provided for this purpose in member 1. Piston member 2 also has an annular part fitting around a reduced part of member 1 and provided with 80 annular packing ring channels or grooves 5 receiving spring snap packing rings 6 and radial bores or conduits 7 communicating with said channels extend therefrom to the 85 inner face of said member 2.

Member 1 is provided at equi-distant 90 points on a circle on both its upper and lower faces with conical recesses 8 communicating with each other by means of a straight cylindrical bore 9 passing vertically through the piston and is also further provided with radial conduits 10 extending from said bores 9 to and registering with 95 their respective radial bores or conduits 7 in the member 2, thus each set of radial bores or conduits 10 and 7 forms communication between one piston ring groove or channel 6 and their respective bore 9. It is to be understood of course that for each bore 9 there will be as many radial bores or conduits 10 and 7 as there are packing ring channels or grooves 6, but two being shown in the present instance by way of illustration, this being the number commonly provided 100 the usual pistons of steam engines for ordinary purposes. Also, it will be un- 110

derstood that this invention may be applied to any form of piston having spring snap ring packing or other non-steam pressure packing.

- 5 Working in each bore 9 is a valve stem 11 square in cross-section with rounded corners to give a good clearance passage for the escaping steam and having its ends cylindrical and externally screw-threaded to receive 10 the internally screw-threaded valves 12, corresponding in size and shape to the recesses 8, the walls of which act as valve seats for the respective valves 12. After the valves 12 have been screwed on the ends of the stem 11 may be spread (Fig. 5) to prevent their 15 screwing off or out of adjustment. The length of the portion of the stem 11 between valves 12 is slightly greater than the length of bore 9, giving the valves a slight play not 20 exceeding a sixteenth of an inch, thus one valve 12 will always be unseated on the exhaust side of the piston and the other valve 12 will always be seated on the pressure side of the piston, excepting during the very 25 slight interval when they are shifting positions toward the end of the stroke of the piston.

All parts above described may be made of any suitable metal or other material, 30 monel metal being preferred for the valves 12.

In operation, the piston having passed its neutral point and advancing, simultaneously with the shifting of the slide valve 35 to supply a new charge, compresses the residuum of the exhaust invariably left in the end of the cylinder and this in compressing acts on the ends of valves 12 on that side of the piston, seating them and through 40 the stems 11 unseating the valves 12 on the now exhausting side of the piston, this action taking place just in advance of the entrance of the new charge of steam into the cylinder. Any of this new charge which 45 works behind the packing rings 6 into grooves 5 may now pass out through radial bores or conduits 7 and 10 to bore 9 and out on the exhaust side of the piston, as indicated by the solid line arrows in Fig. 1, until 50 the end of the stroke is reached, when the above action will be repeated, any steam working behind the packing now passing out in the direction indicated by the dotted arrows in Fig. 1, and so on, the positions of 55 the valves 12 being reversed at the end of each stroke by compression of the residuum of the exhaust just prior to the admission of the new charge.

This invention has been described throughout as applied to a vertically reciprocating piston, but of course may be applied to a piston working in any plane. Also, it is obvious that various changes and modifications may be made in the arrangement, construction, position and shape of the several

parts, bores and conduits of my invention, of which only the preferred form has been illustrated and described herein, without departing from the spirit thereof, and it is my intention and desire to include all such in 70 the following claims.

Having thus described my invention, what I claim as new and desire to secure by Letters Patent is:

1. A piston provided with a bore passing 75 therethrough, a packing ring groove and a conduit forming communication between said groove and bore, in combination with a valve stem working in said bore and a valve mounted on each end of said stem to automatically by compression alternately open communication between said groove and the space on the exhaust side of said piston, and close communication between said groove and the space on the compression side of 85 said piston.

2. A piston provided with a bore passing therethrough, packing ring grooves and conduits forming communication between each groove and the bore, in combination with a valve stem working in said bore and a valve mounted on each end of said stem to automatically open and close communication between said grooves and the space on each side of said piston, the seating faces of said 95 valves being presented toward each other.

3. A piston provided with bores passing therethrough in the direction of travel thereof, annular packing ring grooves and radial conduits forming communication between 100 the respective bores and the grooves, in combination with a valve stem working in each bore and valves mounted on each end respectively of said stem to alternately open and close communication between said 105 grooves and the space on each side of said piston, the communication being open on the exhaust side when closed on the compression side.

4. A piston provided on each exterior face 110 with registering recesses, bores forming communication between each two registering recesses, grooves to receive packing and further provided with conduits forming communication between the respective bores 115 and said grooves, in combination with a valve stem working in each respective bore and a valve fixedly secured to each respective end of said stem, said valves corresponding in size and shape to said recesses and the portion of each stem between its valves being greater in length than its respective bore.

5. A cylinder, a piston working therein and provided on each exterior face with conical registering recesses, cylindrical bores connecting each two registering recesses, annular grooves to receive packing and radial conduits forming communication between the respective bores and said grooves, 130

in combination with packing rings fitting in said grooves, a valve stem approximately angular in cross-section working in each respective bore and a conical valve screwed on 5 the respective ends of said stem and fitting said recesses, the walls of which act as seats therefor, the portion of each stem between its valves being greater in length than its respective bore.

10 6. A piston having longitudinal bores, packing grooves and passages connecting said grooves and bores, in combination with floating valves working in said bores, and, by the compression of the residuum of the 15 exhaust steam, automatically shifted a short distance to open the valves on the exhaust side of the piston.

7. A piston having longitudinal bores,

packing grooves and passages connecting said grooves and bores, in combination with 20 a valve-stem working in each of said bores and valves mounted on the ends thereof and, by the compression of the residuum of the exhaust steam, automatically shifted a distance, not exceeding a sixteenth of an inch, 25 to open the valves on the exhaust side of the piston.

In testimony whereof, I have signed my name to this specification in the presence of the subscribing witnesses.

JOSEPH F. BATTY.
